UNITED STATES PATENT OFFICE

MICHAEL W. MCARDLE, OF CHICAGO, ILLINOIS

DESIGN FOR A COMBINED HOUSEHOLD FOOD MIXER AND JUICE EXTRACTOR

Application filed July 13, 1931. Serial No. 40,516. Term of patent 14 years.

To all whom it may concern:

Be it known that I, MICHAEL W. MCARDLE, a citizen of the United States, residing at Chicago, in the county of Cook and State of Illinois, have invented a new, original, and ornamental Design for a Combined Household Food Mixer and Juice Extractor, of which the following is a specification, reference being had to the accompanying drawing, forming part thereof.

In the drawing—

Figure 1 is a perspective view of a combined household food mixer and juice extractor, showing my new design; and Figs. 2 and 3 are side and front elevations, respectively, thereof.

I claim:

The ornamental design for a combined household food mixer and juice extractor, as shown.

MICHAEL W. MCARDLE.
